SULFOLANE PHARMACEUTICAL
COMPOSITIONS

Bernard Loev, Broomall, Pa., assignor to Smith Kline & French Laboratories, Philadelphia, Pa., a corporation of Pennsylvania
No Drawing. Filed Aug. 29, 1960, Ser. No. 52,348
5 Claims. (Cl. 167—82)

This invention relates to new pharmaceutical compositions comprising solutions containing medicinal agents combined with sulfolane compounds as solvents for said medicinal agents for administration to animal organisms.

Many valuable medicinal agents are extremely insoluble in the usual pharmaceutical solvents. In addition there are many potentially valuable drugs which are either inactive or produce erratic results because of poor solubility. Thus a need exists in the pharmaceutical industry for a nontoxic, inert, water soluble solvent of high solvency power.

The sulfolane solvents used in the pharmaceutical compositions of this invention are powerful solvents for a wide variety of difficultly soluble medicinal agents, such as antibiotics for example chloramphenicol, staphylocycin, griseofulvin and penicillin derivatives; steroids; barbiturates; hydantoins; vitamins; sulfa derivatives; pteridines, such as 2,4,7-triamino-6-phenylpteridine; pyrazoloindene hydrazones such as 3-ethylpyrazolo[3,4-a]inden-4 (1H)-one hydrazone; and alkaloids such as reserpine and rescinnamine. In addition these sulfolanes are useful as reaction solvents, for example they are solvents for the valuable penicillin intermediate, 6-aminopenicillanic acid.

The sulfolane solvents described herein as essential ingredients of these novel compositions are nontoxic in doses greater than 2 g./kg. orally and at this dosage are, in fact, essentially inert and devoid of physiological activity.

The sulfolane solvents useful in the pharmaceutical composition of this invention may be represented by the following formulas:

Formula I

Formula II

when:

R_1 represents hydrogen, methyl, hydroxy, methoxy, ethoxy or allyloxy;

X_1 represents $-\text{NH}-$, $-\text{NR}_3-$, S or O;

X_2 represents hydroxy, OR₃,

R_2 represents lower alkylene having 2-4 carbon atoms; and

R_3 represents lower alkyl having 1-3 carbon atoms.

The compounds of Formula II are particularly advantageous and potent pharmaceutical solvents.

The pharmaceutical compositions according to this invention comprise a solvent of Formula I or Formula II and a medicinal agent substantially soluble in said solvent. The solvent is present in an amount sufficient to dissolve completely the medicinal agent. The solutions usually contain about 1-40% by weight of the medicinal agent, depending of course upon the solubility, potency and desired dosage of the medicinal agent.

The sulfolane solvents are water soluble. Optionally the pharmaceutical compositions of this invention may be diluted with water before administration. When the sol-

2

vent contains an amino group, as in Formula II in which either or both of X_1 and X_2 are amino, it may be desirable to buffer the pharmaceutical composition with an acid-salt buffer combination such as boric acid-sodium borate or citric acid-sodium citrate.

The pharmaceutical composition of this invention may be administered orally per se, orally after dilution with water to give an emulsion or suspension, or parenterally. The composition may be orally administered in gelatin capsules.

The sulfolane solvents are either known to the art or are prepared by reacting 3-sulfolene with the appropriate $\text{HX}_1-\text{R}_1-\text{X}_2$ in the presence of an alkali metal hydroxide such as sodium or potassium hydroxide. The reaction is conveniently carried out in the absence of alkali when the desired compound is a sulfolane of Formula II in which X_1 =amino. The reactants are heated at about 40-60° C. for about 1-3 hours. Neutralization of the alkali and treatment of the solution with saturated salt solution, such as sodium chloride solution, separates the desired sulfolane compound.

Alternatively heating the reactants in a closed bottle with a catalytic amount of an alkali metal hydroxide such as sodium or potassium hydroxide at about 60-75° C. for about 10-72 hours yields the sulfolane compound.

The sulfolane compounds which are contained in the pharmaceutical compositions described herein are non-toxic, inert, water soluble solvents of high solvency power for a wide variety of medicinal agents and thus, surprisingly, have been found to meet a serious, existing need in the pharmaceutical industry.

The following examples are not limiting but are illustrative of the invention.

Example 1

35	Ingredients:	Amounts, g.
	Sulfolane	100
	Phenobarbital	10

Ten grams of phenobarbital is added to 100 g. of sulfolane with stirring to yield a solution. Solution is accelerated by warming to 70-80° C.

Example 2

35 Thirty grams of methylaminoethanol, 23.6 g. of 3-sulfolene and 5 drops of 10% sodium hydroxide solution are mixed and heated in a sealed bottle at 65° C. for three days. On concentration in vacuo an oil is obtained. Benzene and ether are added. The ether layer is concentrated to give 3-(2-methylaminoethoxy)sulfolane.

50	Ingredients:	Amounts, g.
	3-(2-methylaminoethoxy)sulfolane	225
	Chloramphenicol	25

The chloramphenicol is added with stirring to 3-(N-methylaminoethoxy)sulfolane to give a solution.

Example 3

23.6 g. of 2-(N-methylamino)ethanol and 23.6 g. of 3-sulfolene is heated in a pressure bottle at 60° C. for 48 hours. Removal of the volatile materials in vacuo gives 3-[N-(2-hydroxyethyl)-N-methylamino]sulfolane.

60	Ingredients:	Amounts, g.
	3-[N-(2-hydroxyethyl)-N-methylamino]-sulfolane	85
	Sulfaethylthiadiazole	15

The ingredients are mixed to form a solution.

Example 4

3-sulfolene (20 g.) and dimethylaminoethylamine (15.4 g.) are placed in a pressure bottle and heated at 60° C. for

48 hours. The resulting oil is taken up in benzene, charcoal and concentrated to give 3-[2-(N,N-dimethylamino)ethylamino]sulfolane.

Ingredients:	Amounts, g.
3-[2-(N,N-dimethylamino)ethylamino]-sulfolane	45
Staphylocycin	5

The staphylocycin is added with stirring to the sulfolane solvent to form a solution.

Example 5

Nine grams of dimethylaminoethanol, 11.8 g. of 3-sulfolene and 3 drops of 10% sodium hydroxide are heated in a sealed bottle at 70° C. for 12 hours. The resulting mixture is concentrated to give 3-[2-(N,N-dimethylamino)-ethoxy]sulfolane.

Ingredients:	Amounts, g.
3-[2-(N,N-dimethylamino)ethoxy]sulfolane	90
6-aminopenicillanic acid	10

The 6-aminopenicillanic acid is added with stirring to the sulfolane derivative to give a solution.

Example 6

A mixture of diethylaminoethanethiol (13.0 g.), 3-sulfolene (14.8 g.) and 0.3 g. of powdered potassium hydroxide is heated in a pressure bottle for three days at 60° C. The resulting oil is dissolved in benzene. The solution is filtered and concentrated. The residue is converted to the picrate salt which is dissolved in acetonitrile and passed through an alumina column to decompose the picrate. Acetone is passed through the column. The resulting solution is treated with ethereal hydrogen bromide to separate 3-(2-diethylaminoethylthio)sulfolane hydrobromide.

An aqueous solution of the hydrobromide is neutralized with sodium hydroxide to give 3-[2-(N,N-diethylamino)-ethylthio]sulfolane.

Ingredients:	Amounts, g.
3-[2-(N,N-diethylamino)ethylthio]sulfolane	140
Reserpine	10

Reserpine (10 g.) is added with stirring to the sulfolane to give a solution.

Example 7

To 4.7 g. of potassium hydroxide dissolved in 68 mL of methyl Cellosolve is added 100 g. of 3-sulfolene. The mixture is kept at 40° C. for 24 hours, then neutralized with hydrochloric acid. Washing with saturated sodium chloride, drying and distilling gives 3-(2-methoxyethoxy)sulfolane.

Ingredients:	Amounts, g.
3-(2-methoxyethoxy)sulfolane	150
Griseofulvin	10

The ingredients are mixed to form a solution.

Example 8

A mixture of 11.6 g. of N-propylpropane-1,3-diamine and 11.8 g. of 3-sulfolene is heated in a pressure bottle at 55° C. for 48 hours to give 3-[3-(N-propylamino)propylamino]sulfolane.

Ingredients:	Amounts, g.
3-[3-(N-propylamino)propylamino]-sulfolane	90
Sulfisoxazole	10
Sodium borate	0.02
Boric acid	0.48

Sulfisoxazole is added slowly with stirring to the sulfolane solvent containing sodium borate and boric acid to give a solution.

Example 9

Potassium hydroxide (0.4 g.) is added to 14.4 g. of N,N,N'-triethylaminoethylamine. To this mixture is

added 11.8 g. of 3-sulfolene. After heating at 50° C. for two hours, an amount of hydrochloric acid sufficient to neutralize the potassium hydroxide is added and the mixture is then treated with saturated sodium chloride solution. 3-[N-ethyl-N-(2-diethylaminoethyl)amino]sulfolane separates from the mixture.

Ingredients:	Amounts, g.
3-[N-ethyl-N-(2-diethylaminoethyl)amino]sulfolane	90
Testosterone propionate	10

The ingredients are mixed to give a solution.

Example 10

Potassium hydroxide (0.4 g.) is added to 8.2 g. of 1,4-propanediol. To this mixture is added 11.8 g. of 3-sulfolene and the resulting solution is heated at 50° C. for two hours. Neutralizing with hydrochloric acid and washing with saturated sodium chloride solution separates 3-(4-hydroxybutoxy)sulfolane.

Ingredients:	Amounts, g.
3-(4-hydroxybutoxy)sulfolane	9.5
Vitamin B ₁₂	0.5

The vitamin B₁₂ is added slowly with stirring to 3-(4-hydroxybutoxy)sulfolane to give a solution.

Example 11

A mixture of 11.7 g. of 1-methyl-2-propoxyethylamine and 11.8 g. of 3-sulfolene is heated in a pressure bottle at 55° C. for 72 hours to give 3-(1-methyl-2-propoxyethylamino)sulfolane.

Ingredients:	Amounts, g.
3-(1-methyl-2-propoxyethylamino)sulfolane	9.5
Cortisone	0.5

The ingredients are mixed together and stirred until a solution is formed.

Example 12

Ingredients:	Amounts, g.
3-methylsulfolane	25
4-chloro-19-nortestosterone acetate	5

The testosterone derivative is added to 3-methylsulfolane to form a pharmaceutical solution.

Example 13

Allylalcohol (5.6 g.) and 3-sulfolene (11.8 g.) are mixed and heated in a pressure bottle at 50° C. for 48 hours. The resulting oil is taken up in benzene, treated with charcoal, filtered and concentrated in vacuo to give 3-allyloxy-sulfolane.

Ingredients:	Amounts, g.
3-allyloxy-sulfolane	9.0
Rescinnamine	1.0

One gram of rescinnamine is added with stirring to nine grams of 3-allyloxy-sulfolane to give a solution.

Example 14

Dipropylaminoethanol (14.5 g.), potassium hydroxide (0.4 g.) and 11.8 g. of 3-sulfolene are heated at 60° C. for 90 minutes. Neutralizing with hydrochloric acid and washing with saturated sodium chloride gives 3-[2-(N,N-dipropylamino)ethoxy]sulfolane.

Ingredients:	Amounts, g.
3-[2-(N,N-dipropylamino)ethoxy]sulfolane	90
Sulfathiazole	10

The ingredients are mixed together to form a solution.

Example 15

Ingredients:	Amounts, g.
3-methoxysulfolane	9.8
Phenoxymethylpenicillin	0.2

The ingredients are combined and stirred to form a solution.

Example 16

Ingredients:	Amounts, g.
3-hydroxysulfolane	9.5
Diphenylhydantoin	0.5

The ingredients are mixed and warmed to 80° C. to form a solution.

Example 17

A mixture of 11.8 g. of 3-sulfolene, 3.2 g. of ethanol and 3 drops of 10% sodium hydroxide is heated in a sealed tube for 24 hours at 60° C. to give 3-ethoxysulfolane.

Ingredients:	Amounts, g.
3-ethoxysulfolane	9.8
2,4,7-triamino-6-phenylpteridine	0.2

The ingredients are mixed and warmed to 70° C. to give a pharmaceutical solution.

Example 18

Ingredients:	Amounts, g.
3-[N-(2-hydroxyethyl)-N-methylamino]-sulfolane	7.5
3-ethylpyrazolo[3,4-a]-inden-4(1H)-one hydrazone	2.5

The ingredients are stirred to form a solution.

What is claimed is:

1. A pharmaceutical composition comprising a solvent selected from the group consisting of:

6

in which R₁ is a member selected from the group consisting of hydrogen, methyl, hydroxy, methoxy, ethoxy and allyloxy; X₁ is a member selected from the group consisting of —NH—, —NR₃—, S and O; X₂ is a member selected from the group consisting of hydroxy, —OR₃,

10 R₂ is lower alkylene having 2-4 carbon atoms and R₃ is lower alkyl having 1-3 carbon atoms; and a difficultly soluble medicinal agent substantially soluble in said solvent.

15 2. A pharmaceutical composition in accordance with claim 1 in which said solvent is present in an amount sufficient to dissolve completely said medicinal agent.

3. A pharmaceutical composition in accordance with claim 1 in which said medicinal agent is selected from the group consisting of antibiotics, steroids, barbiturates, hydantoins, vitamins, sulfa derivatives, pteridines, pyrazolindene hydrazones and alkaloids.

4. A pharmaceutical composition comprising 3-[N-(2-hydroxyethyl)-N-methylamino]sulfolane and a difficultly soluble medicinal agent substantially soluble therein.

20 5. A pharmaceutical composition comprising 3-(2-methylaminoethoxy)sulfolane and a difficultly soluble medicinal agent substantially soluble therein.
